[57] CLAIM

The ornamental design for a cab for a harvesting machine, as shown.

DESCRIPTION

FIG. 1 is a front elevational view of a cab for a harvesting machine showing our new design;

FIG. 2 is a rear elevational view thereof;

FIG. 3 is a side elevational view taken from the left of FIG. 1;

FIG. 4 is a side elevational view taken from the right of FIG. 1;

FIG. 5 is a top plan view as seen in the direction of line 5—5 of FIG. 4;

FIG. 6 is a cross-sectional view taken along line 6—6 in FIG. 4;

FIG. 7 is a right front perspective view thereof; and

FIG. 8 is a left rear perspective view thereof.
